Primary Examiner — Darlington Ly*Assistant Examiner* — Giang Hoang Tran(74) *Attorney, Agent, or Firm* — IPkey PLLC(57) **CLAIM**

The ornamental design for an all-terrain vehicle, as shown and described.

DESCRIPTION

FIG. 1 is a top, front and right side perspective view of the all-terrain vehicle in accordance with the new design;

FIG. 2 is a top, rear and left side perspective view thereof;

FIG. 3 is a front elevation view thereof;

FIG. 4 is a rear elevation view thereof;

FIG. 5 is a left side elevation view thereof;

FIG. 6 is a right side elevation view thereof; and,

FIG. 7 is a top plan view thereof.

The broken lines showing various portions of the all-terrain vehicle are for the purpose of illustrating context and form no part of the claimed design.

The portions of the all-terrain vehicle shown in faded color lines and outlined with a long-dashed, short-dashed line pattern form no part of the claimed design.
